COMBINED SAFETY JOINT AND JAR

James G. Richey, Alhambra, Calif.

Application November 22, 1939, Serial No. 305,636

5 Claims. (Cl. 255—27)

My invention relates generally to oil well tools and appliances and more particularly to a combined safety joint and jar and my present invention is an improvement on the Oil well tool vibrator patented by me November 3, 1931, No. 1,829,758.

The principal objects of my present invention are, to generally improve upon the construction of the oil well tool vibrator or jar disclosed in my aforesaid patent, as well as other existing forms of jars and vibrators and further, to provide a tool of the character referred to which, in addition to providing a safety joint between the lower end of the drill pipe and the tool or device that is connected to the lower end thereof, also functions as a jar or vibrator for imparting hammer-like blows or impulses directly to a drill or other tool that has become lodged or "stuck" in the formation at the lower end of the well hole and which jarring action is generally effective in loosening the drill or other implement so that the same may continue to perform its intended functions.

Further objects of my invention are, to provide a device of the character referred to that may be easily and quickly disconnected from the drill, packer or other implement that is carried at the lower end of the drill string, further, to construct the safety joint and jar so that fluid may readily circulate therethrough and further, to provide the tool with simple and efficient means that acts automatically to prevent the sleeve or bowl portion of the tool from unscrewing from the threaded mandrel as a result of the weight of said sleeve, when the drill string and tool carried thereby are elevated so as to lift the lower end of the drill, reamer or like implement from the formation at the bottom of the well hole.

Further objects of my invention are, to construct the safety joint and jar so as to effectively prevent mud, fluid and the like from entering the chamber between the externally threaded mandrel and the internally threaded sleeve or bowl that co-operates with the mandrel in producing the jars or impulses transmitted to the tool or implement carried at the lower end of the drill string and further, to provide means for minimizing the friction between the co-operating threads on the mandrel and the sleeve while the drill string and mandrel that is connected thereto are being rotated.

With the foregoing and other objects in view, my invention consists in certain novel features of construction and arrangement of parts that will be hereinafter more fully described and claimed and illustrated in the accompanying drawing in which:

Fig. 1 is a cross section taken lengthwise through the center of my improved safety joint and jar and showing the drill string and mandrel

in elevated position relative to the sleeve or bowl.

Fig. 2 is a vertical section similar to Fig. 1 showing the mandrel at the lower end of its movement within the sleeve or bowl.

Fig. 3 is an elevational view of the threaded mandrel and the sub or coupling that is utilized for connecting the mandrel to the lower end of the drill string.

Fig. 4 is a horizontal section taken on the line 4—4 of Fig. 1.

Fig. 5 is a horizontal section taken on the line 5—5 of Fig. 2.

Fig. 6 is a horizontal section taken on the line 6—6 of Fig. 2.

Fig. 7 is an elevational view of a portion of the internally threaded sleeve or bowl that encloses and co-operates with the mandrel, with parts broken away and in section.

Fig. 8 is a cross section taken approximately on the line 8—8 of Fig. 2 and looking upwardly against the tubular member which projects from the upper end of the sleeve and receives the lower portion of the sub.

Fig. 9 is an elevational view partly in section of the brake or friction device utilized for preventing the mandrel from becoming accidentally unscrewed from the sleeve or bowl.

Fig. 10 is a detail sectional view showing the anti-friction means utilized between the inter-engaging threads on the mandrel and sleeve.

Referring by numerals to the accompanying drawing which illustrates a preferred embodiment of my invention, 10 designates the lowermost portion of the lower member of the drill string, which lower portion is internally threaded for the reception of the externally threaded pin or plug portion 11 that is formed on the upper end of the cylindrical body 12 of a sub or coupling.

Formed integral with or rigidly secured to the lower end of the coupling member 12 is a tubular mandrel 13, the duct through which communicates with an axial duct 14 that is formed through the coupling member 12 and the threaded pin 11 at the upper end thereof.

Screw seated in the lower end of the mandrel is the upper portion of a wash or circulation pipe 15, which latter extends axially downward through the sub or coupling member 16 that is utilized for connecting the combined safety joint and jar to the drill, reamer, packer, or other appliance that is carried by the lower end of the drill string.

The members forming the drill string are tubular and thus the duct 14, passage-way through mandrel 13 and the pipe 15 provide means whereby circulation fluid or mud may be pumped downwardly to the tool or appliance carried by the lower end of the drill string.

The upper end portion of sub 16 is externally

threaded for engagement in the internally threaded lower end of a sleeve or bowl 17 which encloses the mandrel 13 and formed integral with or secured to the upper end of this sleeve is a short tubular extension 18 that has sliding engagement with the lower portion of the sub or coupling member 12.

The internal diameter of sleeve 18 is slightly larger than the internal diameter of sleeve 17.

Formed on the sub or coupling member 12 is a circumferential shoulder 19 which, when the sub is at its lower limit of movement, occupies a position immediately adjacent the upper end of the tubular extension 18, but during the operation of the tool there is no jarring action between said shoulder 19 and the upper end of member 18.

When the sub 12 is at its lower limit of movement with respect to the sleeve 17 as illustrated in Fig. 2, the upper end of said sleeve bears directly against a shoulder on the lower end of the lower portion of the sub or that portion that is surrounded by the tubular extension 18, and this engagement cooperates with the engagement between the upper end of tubular extension 18 and shoulder 19 in effectually preventing telescopic movement of the sub 12 and sleeve 17 toward each other.

Formed in that portion of the sub that is enclosed by the tubular extension 18 is a circumferential groove 20 that receives a suitable packing 21, thereby preventing circulation fluid and mud from passing through the joint between the lower portion of sub 12 and tubular member 18 into the chamber within the sleeve 17 that is occupied by the co-operating threads on the mandrel and sleeve.

To pack the joint between the circulation pipe 15 and the lower portion of the sleeve 17 that receives the sub 16, a packing 22 occupies a groove formed in sleeve 17 around the opening through which the pipe 15 passes and this packing is retained in position by a packing nut 23 that is screwed seated in sleeve 17 at the bottom of the threaded recess that receives the threaded end of the sub 16.

Formed integral with the mandrel 13 on the surface thereof is a thread, preferably square in cross section and which is interrupted by having portions cut away so as to leave a plurality of convolutions 24, each of which is slightly less than three hundred sixty degrees in length. In other words, each thread portion does not extend entirely around the mandrel, but is formed so that a slight space is produced between the ends of the thread portion, one end being disposed above the other with a space equal to the width of the thread between said ends.

Formed integral with the sleeve or bowl 17 on the interior thereof is a thread that is interrupted by having portions cut away to form a series of thread sections 25, preferably square in cross section and which are adapted to engage and cooperate with the corresponding thread sections 24 on the mandrel. The length of the threads 25 on the sleeve is practically the same as the threads 24 on the mandrel, namely, a little less than three hundred sixty degrees so that the ends of said threads are spaced apart circumferentially of the sleeve a few degrees and vertically a distance equal to or slightly greater than the width of the thread sections 24.

Formed integral with or fixed to the upper portion of mandrel 13 is a lug 26 that provides a stop against which the upper end of the uppermost one of the thread members 25 on the sleeve is

adapted to engage, thus limiting the upward movement of the sleeve on the mandrel and likewise limiting the downward movement of said mandrel within said sleeve.

In order to produce sufficient friction between the mandrel carrying sub 12 and the sleeve 17 to prevent said sleeve from unscrewing from the mandrel and dropping off the lower end of the drill string while the same is being elevated or pulled upwardly through the drill hole, a brake of the over-running clutch type and illustrated in Figs. 4, 8, and 9 is arranged on the mandrel between the stop lug 26 and the lower end of the body of the sub 12.

This friction device includes a plurality of short vertically disposed rollers 27 that are positioned in pockets formed between the ends of blocks 28, the latter being suitably secured to the mandrel 13 and which rollers in moving through the pockets roll upon inclined faces 29 that are formed on the periphery of the mandrel and which form the bottoms of said pockets. These rollers are normally pressed toward the high portions of the inclined faces 29 by expansive springs 30 that are arranged between said rollers and the ends of the blocks 28.

Each roller is provided on its ends with axially disposed pins 31 which occupy inclined slots 32 that are formed in cage rings 33 and which latter are disposed above and below the rollers 27 and blocks 28.

As a result of this construction, the rollers 27 under the influence of the expansion springs 30 tend to roll up the inclined surfaces 29 and consequently moving radially outward to frictionally engage the inner surface of the sleeve or bowl 17 and thus, when the drill string is pulled upwardly through the well hole the sleeve will be prevented from becoming accidentally unscrewed from the mandrel due to the weight of said sleeve and the parts carried thereby.

Where the jar is constructed so as to rotate clockwise or toward the right hand as illustrated in the drawing, the tool is "made up" until the parts occupy the positions as illustrated in Fig. 2, with the upper end of the sleeve 17 bearing against the shoulder at the lower end of the sub 12 and which shoulder is just above and surrounds the clutch. When so positioned, the clutch is disposed within the upper portion of the sleeve 17 with the rollers of said clutch bearing against the inner face of the sleeve. Thus the sleeve is locked to the sub in its elevated position with respect to the mandrel by the clutch and the parts occupy these positions while the tool and drill string are being lowered into the well, and likewise they occupy such positions if the tool is "made up" after having been run into the well with the lower end of the drill carried by the sleeve, resting on the bottom of the well hole. Thus the clutch holds the sleeve and drill from running off the mandrel while the tool and drill string are being run into the hole, and during drilling operations as the string is rotated toward the right hand the parts retain their "made up" positions so that the tool operates as a single piece while drilling.

To impart downward jar to the sleeve and drill carried thereby, the drill string is rotated toward the left hand and at the same time with an upward pull or stress, which action disengages the rollers of the clutch from the inner face of the upper end of the sleeve, such movement requiring about a half turn. Such action positions the threads on the mandrel above the threads on

the sleeve and the drill string is now rotated toward the left hand without the upper stress or pull and when the threads on the sleeve ride off the threads on the mandrel and having been elevated slightly as a result of the engagement between the two sets of threads, said threads move downwardly to strike the next lower threads on the mandrel, thereby imparting downward jar thereto. It will be understood that this dropping of the drill string and mandrel is possible due to the fact that both sleeve and mandrel are provided with co-operating threads of the mutilated type.

To impart upward jarring movement to the sleeve and tool carried thereby, the drill string is rotated toward the left hand with upward stress until the threads on the sleeve and mandrel are disengaged and the drill string is then rotated toward the right hand with continued upward stress, with the result that the threads on the mandrel will strike against the under faces of the threads on the sleeve, thus producing the upward jar to said sleeve and parts carried thereby.

To resume drilling after jarring operations, the drill string is of its own weight lowered until the shoulder at the upper end of the sleeve engages the lower end of sub 12 with the clutch disposed within the upper portion of the sleeve and the drill string is now rotated toward the right hand to make up the jar, with the parts occupying the positions as illustrated in Fig. 2. At such time the clutch secures the upper end of the sleeve to the lower end of the sub.

While imparting either upward or downward jarring movement to the sleeve and tool carried thereby, the clutch is positioned above the upper end of sleeve 17 and which condition is possible due to the spacing of the thread sections on the interior of the sleeve and on the mandrel. In this connection, it will be noted that the thread sections on both sleeve and mandrel are arranged in pairs and which pairs are spaced apart a distance equal to one complete thread convolution.

To release the mandrel from the sleeve and drill carried thereby, the drill string is rotated toward the left hand with an upward stress, and thus the mandrel will be unscrewed from the sleeve, thus enabling the drill string to be withdrawn from the well hole, leaving the sleeve and tool therein.

In order to decrease the friction between the co-operating faces of the interrupted threads on the mandrel and sleeve when the mandrel carried by the drill string is being rotated, rollers 34 of hardened metal are loosely mounted in recesses formed in the upper portions of the thread sections 24 and the peripheries of these rollers project just above the upper surfaces of the threads so as to provide an anti-friction support for the threads 25 on the sleeve when the threads 24 and 25 are in engagement with each other (see Fig. 10).

Thus it will be seen that I have provided a combined safety joint and jar that is relatively simple in construction, inexpensive of manufacture and very effective in performing the functions for which it is intended.

The device is provided with a duct which enables circulation fluid to readily flow from the drill string to the tool carried by the lower end thereof and the joints between the mandrel and sleeve are effectively packed so as to prevent any of the circulation fluid from entering the cham-

ber in which the cooperating thread sections on the mandrel and sleeve are located.

Further advantages of my improved construction are the brake or clutch structure which is effective in locking the sleeve to the mandrel so that said sleeve can not unscrew and drop off the mandrel while said sleeve is being withdrawn from the well, also the anti-friction members located in the upper surfaces of the thread sections on the mandrel for minimizing friction between said thread sections and the thread sections on the sleeve while the mandrel is under upward strains.

It will be understood that minor changes in the size, form and construction of the various parts of my improved combined safety joint and jar, may be made and substituted for those herein shown and described, without departing from the spirit of my invention, the scope of which is set forth in the appended claims.

I claim as my invention:

1. In a combined safety joint and jar, a mandrel, a sleeve enclosing said mandrel, co-operating interrupted threads on said mandrel and sleeve and means carried by said mandrel for automatically gripping said sleeve to prevent the same from unscrewing from the mandrel as a result of the weight of said mandrel and the parts carried thereby when the same are lifted from the bottom of the well hole.

2. In a combined safety joint and jar, a mandrel, a sleeve surrounding said mandrel, co-operating interrupted threads on said mandrel and sleeve, a shoulder on said mandrel against which the upper end of the thread on the sleeve engages so as to limit the downward movement of the mandrel into said sleeve and means carried by the mandrel and positioned in the upper portion of the sleeve when the mandrel is at the lower end of its travel downwardly into said sleeve for automatically gripping said sleeve and preventing the same from unscrewing from the mandrel as a result of the weight of said sleeve and the parts carried thereby when the same are lifted from the bottom of the well hole.

3. A combined safety joint and jar as set forth in claim 2, with means for producing a fluid tight joint between said mandrel and sleeve above the sleeve gripping means carried by said mandrel.

4. A combined safety joint and jar, a mandrel, a sleeve surrounding said mandrel, the lower portion of which sleeve is internally threaded for the reception of the threaded end of a tool or a tool carrying sub, a plurality of spaced pairs of interrupted threads on said mandrel, a plurality of cooperating spaced interrupted threads on the interior of said sleeve and means carried by the mandrel for automatically gripping the sleeve to prevent the latter from unscrewing from the mandrel as a result of the weight of said sleeve and parts carried thereby when the same are lifted from the bottom of the well hole.

5. In a combined safety joint and jar, a mandrel, a sleeve surrounding said mandrel, co-operating interrupted threads on said mandrel and sleeve, means for limiting the movement of the mandrel and sleeve longitudinally toward each other and means on the mandrel for gripping the sleeve to prevent the same from unscrewing from said mandrel due to the weight of said sleeve and parts carried thereby as the same are lifted from the bottom of the well hole.

JAMES G. RICHEY.
